UNITED STATES PATENT OFFICE.

ALEXANDER GORDON, OF DETROIT, MICHIGAN.

PRESS FOR CIGAR-MOLDS.

1,128,598.

Specification of Letters Patent. Patented Feb. 16, 1915.

Application filed January 29, 1914. Serial No. 815,115.

To all whom it may concern:

Be it known that I, ALEXANDER GORDON, a citizen of the United States of America, residing at Detroit, in the county of Wayne and State of Michigan, have invented certain new and useful Improvements in Presses for Cigar-Molds, of which the following is a specification, reference being had therein to the accompanying drawings.

This invention relates to presses, and more particularly to a hand press employed for exerting a pressure upon cigar-molds.

My invention aims to provide a press of the above type wherein positive and reliable means are employed, as hereinafter set forth, for maintaining a yieldable pressure upon a cigar-mold, whereby after the press has been operated the presser head thereof can yield and preclude any possibility of cigars within the mold being subjected to excessive pressure and imperfect formation.

My invention further aims to provide a press of the above type having tension devices that can be easily and quickly adjusted to regulate the yielding proclivities of the press.

My invention will be better understood when reference is had to the drawings and the detail description thereof.

In the drawings, Figure 1 is a vertical sectional view of the press, partly in elevation, showing the presser head thereof in a lowered position; Fig. 2 is a detail view of the operating mechanism of the presser head showing the same in a reverse position to that illustrated in Fig. 1, and Fig. 3 is a front elevation of the press partly broken away and partly in section illustrating one of the tension devices.

In the drawings, the reference numeral 1 denotes a hollow metallic base substantially rectangular in plan and adapted to be suitably secured to a table or other support.

The base 1 has the sides thereof provided with off-set portions or bosses 2 in which are mounted the lower ends of oppositely disposed posts or uprights 3, said posts having the upper ends thereof reduced, as at 4, to provide annular supporting shoulders 5.

Slidably mounted upon the reduced ends 4 of the posts 3 and normally supported by the annular shoulders 5 are the tubular ends or sleeves 6 of a cross head 7. The sleeves 6 are yieldably held upon the shoulders 5 by coiled compression springs 8 encircling the

upper ends of the posts, said springs being retained thereon by nuts 9 screwed upon the threaded ends of said posts. The springs 8 and the nuts 9 constitute tension devices 60 which can be easily and quickly adjusted to regulate the yieldability of the cross head 7 relatively to the base 1.

The cross head 7, intermediate the ends thereof, has a vertically disposed tubular 65 guide 10 and the upper end of said guide is formed integral with oppositely disposed vertical lugs or brackets 11 having apertured ears or bearings 12 and transverse pivot pins or trunnions 13. The pivot pins 70 or trunnions 13 pivotally support the enlarged portion 14 of an operating lever 15. The enlargement 14 has the outer end thereof beveled, as at 16, and the lower side thereof bifurcated and provided with apertured ears 17. The ears 17 are connected by a transverse pivot pin 18 and pivotally mounted upon said pin, between the ears 17, is the upper end of a link 19. The lower end of the link 19 is pivotally mounted by 80 a transverse pin 20 in the upper bifurcated end 21 of a rod 22 slidably mounted in the tubular guide 10 of the cross head 7. Secured upon the lower end of the rod 22 by a pin 23 or other fastening means is a 85 presser head 24, which is supported normally in parallelism with the base 1.

The enlargement 14 of the operating lever 15 has the bottom side thereof provided with a stop or supporting lug 25 90 adapted to engage the upper end of the tubular guide 10 and support the operating lever 15 in a lowered position. The operating lever 15 is retained in a raised position by a flat spring or resilient arm 26 95 adapted to engage the beveled end 16 of the operating lever, said spring being secured to the front side of the tubular guide 10 by screws 27 or other fastening means.

As illustrated in Fig. 1 of the drawings, 100 the presser head 24 is at the limit of its down stroke and with a mold upon the base 1, the mold would be subjected to pressure. Any tendency of the presser head 24 to move the operating lever 15 is prevented by 105 reason of the pivot pin 18 being out of alignment with the pivot pin 20 and the pivot of the operating lever 15, also by reason of the stop 25 engaging the tubular guide 10. Since the presser head 24 is locked 110 relatively to the operating lever 15, the tension devices are brought into action should

it be necessary for the presser head 24 to yield after having been brought into engagement with the top of a mold. It is therefore apparent that in order for the presser head 24 to yield relatively to the mold that the cross head 7 is raised upon the reduced ends 4 of the posts 3 and the degree of yielding can be regulated by the nut 9.

In the manufacture of cigars, it is essential that compact and easily operated hand presses be employed for expeditiously subjecting molds to the requisite degree of pressure, and it is also desirable that the pressure be of a yielding character in order to prevent cigars from being injured or too tightly packed. For the above reasons, I have designed the press herein described which permits of a mold being easily placed in the same and subjected to pressure while another mold is being prepared. The tension devices permit of the cross head 7 bodily shifting after the presser head has been lowered, consequently if there is an excessive pressure at the beginning, such pressure is immediately relieved by the tension devices. This is a desideratum in the manufacture of cigars and renders an operation that has heretofore required considerable skill comparatively easy for an apprentice or those not thoroughly versed in making cigars.

I am aware of hand presses having been used for exerting a pressure upon cigar molds. For instance, in my Patent 789,906, granted May 16, 1905, there is illustrated a press having a throat that is integral with the base and in connection with this type of press, it was found that there was a certain degree of elasticity, which prevented an excessive pressure, but this type of press was subject to fracture at the base of the throat and the degree of elasticity was limited, while in my improved press provision is made for regulating the yielding of

the presser head by simply adjusting the tension devices. Furthermore, I attach considerable importance to the fact that the operating lever of my improved press can be locked against accidental displacement and that if there is any excessive pressure it is necessary for the entire upper part of the press to yield, which is automatically accomplished while a mold is being prepared to replace the one in the press.

One embodiment of my invention has been illustrated, but it is to be understood that the structural elements are susceptible to such variations and modifications as fall within the scope of the appended claim.

What I claim is:

In a press for cigar molds, the combination of a base, uprights carried thereby and provided with annular shoulders, a cross head with the ends thereof on the shoulders of said uprights, tension devices carried by the upper ends of said uprights, a tubular guide central of said cross head, brackets carried thereby, a rod slidable in said guide, a presser head carried by the lower end of said rod, an operating lever pivoted between said brackets, a link connecting said operating lever to the upper end of said rod, and a flat spring secured to the front side of said tubular guide and extending upwardly at an angle to the longitudinal axis of said guide and adapted to be engaged by the upper side of said operating lever when released and actuated by said tension devices to hold said lever in substantially a vertical position.

In testimony whereof I affix my signature in presence of two witnesses.

ALEXANDER GORDON.
